Des. 190,974
Patented July 25, 1961

190,974

DISPLAY TRAY FOR BOTTLES OR THE LIKE

Benjamin Salis, 1694 Stewart Ave., New Hyde Park, N.Y.

Filed July 11, 1960, Ser. No. 61,290

Term of patent 14 years

(Cl. D58—13)

FIG. 1

FIG. 2

FIG. 3

FIG. 1 is a perspective view of a display tray for bottles or the like, showing my new design;

FIG. 2 is an end elevational view thereof; and
FIG. 3 is a side elevational view thereof.

I claim:

The ornamental design for a display tray for bottles or the like, as shown.
